COMBINED TIE PLATE AND RAIL RETAINING STRUCTURE

Filed March 19, 1949

UNITED STATES PATENT OFFICE

2,522,314

COMBINED THE PLATE AND RAIL
RETAINING STRUCTURE

Lee Spencer, Phoenix, Ariz.

Application March 19, 1949, Serial No. 82,401

5 Claims. (Cl. 238—315)

1

This invention relates to improvements in rail retaining devices of the general class which includes the combination of a tie plate and a rail anchor device which together secure the rail to a crosstie with capacity for limited vertical movement of the rail with respect thereto and also resists lengthwise creeping movement of the rail across the tie plate in the direction of the moving traffic.

A principal object of the invention is to fasten a railroad rail to a crosstie and to provide for limited vertical movement of the rail with respect to the crosstie, the arrangement being characterized by a conventional tie plate which is slotted to receive a rail anchor, the latter of which is driven transversely of the rail into clamping engagement with the base portion of the rail, the rail anchor impinging against a wall of the slot and transmitting the rail creeping stress into the tie plate, and the rail anchor also cooperating with a member which bridges the slot formed in the tie plate and extends over the upper jaw of the rail anchor so as to prevent distortion of the rail anchor during the presence of an abnormal wave motion of the rail.

Another object of the invention is to provide a simplified structure to enable the rail anchor to be driven into engagement with the base flange of the rail and secure the rail against creeping movement, the tie plate underlying the rail being provided with a slot of a definite dimension which prevents overdriving of the rail anchor and consequently avoids excessive distortion of the hook end of the anchor and impairment of its resilience.

Other objects and important features of the invention will be apparent from a study of the description hereinafter, taken together with the drawing, which relates to a certain preferred embodiment of the invention. While the invention is described in terms of a certain preferred embodiment thereof, its scope is not intended to be limited in terms of said embodiment, nor otherwise than by the terms of the appended claims.

In the drawing:

Fig. 1 is a plan view of an improved rail fastening device according to the present invention;

Fig. 2 is a section taken along the line 2—2 of Fig. 1, certain parts being shown in side elevation; and

Fig. 3 is a front elevation view thereof.

Referring to the drawing, the improved rail fastening structure is generally indicated at 10 and is shown as applied to a track rail 11, the

2

base flange 12 and the web 13 only of the rail 11 being shown. The base flange 12 of the rail 11 seats on a tie plate 14, which is firmly secured to a crosstie 16 by track spikes 17 passing through apertures 18 formed in the tie plate 14 in a manner well known in the art.

The lateral thrusts of the rail 11 are resisted by means of a pair of spaced abutments 19 and 21 formed on the tie plate 14 and positioned to engage opposite edge portions of the base 12.

In order to prevent creeping of the rail 11 with respect to the crossties a rail anchoring device is applied to the base flange 12 of the rail 11 to transmit the rail creeping stresses to the tie plates and ultimately into the crossties. The rail anchoring device, herein designated generally at 22, is formed by bending a bar of substantially square cross-section into such configuration as to provide a hook at one end. The hook portion of the rail anchor 22 provides upper and lower jaws which grip the top and bottom surfaces, respectively, of the rail base 12 at one side of the rail, when the rail anchor 22 is driven to its applied position. Thus the rail anchor 22 is provided with a main body portion 23 which bears against the bottom surface 24 of the rail base 12 and forms said lower jaw 25 and said upper jaw 26. The upper jaw is provided with a surface 27 which bears against an upper surface 28 of one flange of the rail base 12.

The main body 23 of the rail anchor 22 is adapted to fit slidably into a slot 29 formed in the tie plate 14, the slot being formed with perpendicular walls so that it can be readily formed by simplified punching operations. In the form of tie plate shown, the slot 29 extends through the edge 31 so as to facilitate the insertion of the body portion 23 of the anchor device beneath the rail base in a position to engage the upper jaw over one flange of the rail base.

In forming the rail anchor 22, the end remote from the jaw 26 is offset as indicated at 33 to provide a shoulder 34 which bears against an edge 36 of the rail base 12. In positioning the rail anchor 22 in clamping engagement with the base flange 12, the main body 23 is brought under the base flange 12 and driving force is applied to the return bend of the hook until the shoulder 34 snaps into place against the edge 36 of the base flange 12.

A small amount of clearance is provided between the end of the offset portion 33, as shown at 37, and the end 32 of the slot 29. The provision of the clearance 37 insures that the rail anchor 22 can snap into position, and also in-

sures that the rail anchor cannot be overdriven to any appreciable extent, such overdriving and consequent spreading of the upper and lower jaws being prevented by the engagement of the end of the body 23 with the end 32 of the slot 29.

It will be seen that with the rail anchor 22 clamped into the position shown in Figs. 1 to 3, the creeping stress will be transmitted by the rail anchor 22 into the tie plate 14 and thence into the crosstie.

It is desirable to secure the rail 11 to the crosstie 16 with capacity for limited vertical movement of the rail relative to the crosstie. Otherwise the normal vertical wave movement of the rail, incident to the passing of traffic thereover, exerts a vertical pulling force on the fastening spikes or imparts vertical pumping of the crossties in the ballast of the roadbed. According to the present invention means are provided for enabling the rails to have the normal amount of wave motion and, at the same time, preventing creeping movement of the rails. To this end the slotted tie plate 14 is provided with a substantially square shaped lug 38 having a square aperture 39 through which the upper jaw 26 of the rail anchor extends. As shown in Fig. 3, the lug 38 includes an arm 41 which overlies the upper jaw 26 and an arm 42 which underlies the said jaw 26. The arm 42 is welded to the slotted tie plate 14 and spans the slot 29 therein, the arm 42 being situated between a gap 43, 44 formed in the abutment 21, and normally presenting a face 46 which is in the same plane as the inner face of the abutment 21.

In forming the rail anchor 22 the lower jaw thereof is given a slight amount of reverse bend as at 47 to provide suitable clearance 48 between the main body 23 and the lower side of the arm 42. The aperture 39 in the lug 38 is of such a dimension that a same amount of clearance 49 is maintained between the lower side of the upper arm 41 and the top surface of the upper jaw 26 of the rail anchor. It will thus be seen that the vertical wave motion of the rail 11 will at times raise the rail 11 with the rail anchor 22 until the lower jaw of the anchor engages with the lower arm 42 of the lug 38 and until the upper jaw 26 is in contact with the upper arm 41 of said lug 38. It will be seen that any abnormal upward movement of the rail base will not impose an upward force on the upper jaw tending to spread it relative to the lower jaw, since the arm 41 of lug 38, during such abnormal wave movement of the rail, will engage the upper surface of the jaw 26. The upper and lower arms of the lug also cooperate to provide a double truss reinforcement for the slotted end portion of the tie plate.

It will be seen with reference to Figs. 1 to 3 of the drawing that I have provided an improved form of rail fastening device which will prevent creeping of the rails with respect to the crossties, the creeping stresses so induced being transmitted into the tie plate and thence into the crosstie. According to the present invention, the rails are also enabled to have a certain amount of vertical wave motion with respect to the tie plate, the amount of such movement being controlled by the clearances 48 and 49 between the rail anchor 22 and the arms 41 and 42 of the lug 38. Abnormal wave movements, according to the invention, will not distort or spread the jaws of the rail anchor or in any way lessen its efficiency to transmit creeping stress into the crosstie 16.

While the invention has been described in terms of an embodiment which it may assume in practice, its scope is not intended to be limited in terms of the embodiments shown but only by the terms of the claims here appended.

I claim:

1. In a railway track structure of the class described, a tie plate having an elongated slot, a rail having a base portion adapted to rest on said tie plate, a one-piece rail anchor comprising a body portion extending beneath said rail base and in said elongated slot, a return bent hook contiguous with said body portion and defining upper and lower jaws releasably engageable with one flange of said rail base at one side of the rail, and means for securing the rail on said tie plate with capacity for limited vertical movement with respect to said tie plate comprising means secured to said tie plate at opposite sides of the slot to rigidify the tie plate and having portion for bridging said slot in the plate and positioned above the upper jaw of the rail anchor in spaced relation thereto to hold the rail on the plate and to prevent spreading of the said upper jaw relative to the lower jaw of said anchor in the event of abnormal upward movements of said rail.

2. In a railway track structure of the class described, a tie plate having an elongated slot, a rail having a base flange adapted to rest on said tie plate, a one-piece rail anchor comprising a shank extending beneath said base flange and in said elongated slot, a return bent hook contiguous with said shank and defining upper and lower jaws releasably engageable with said base flange, and means for securing the rail on said tie plate with capacity for limited vertical movement with respect to said tie plate comprising a lug secured to said tie plate and describing a pair of spaced substantially horizontally extending arms adapted to be positioned above and below the upper jaw of the anchor whereby the upper arm of said lug serves as an abutment engaging the top surface of the upper jaw of the anchor to prevent spreading of the rail anchor jaws in the event of abnormal vertical movement of the rail, the lower arm of said lug extending across the elongated slot in said tie plate and secured to said tie plate to provide stiffening means for said tie plate.

3. In a railway track structure of the class described, a tie plate having an elongated slot, a rail having a base flange adapted to rest on said tie plate, a one-piece rail anchor comprising a shank extending beneath said base flange and in said elongated slot, a return bent hook contiguous with said shank and defining upper and lower jaws releasably engageable with the top and bottom surfaces of said base flange, an integral detent at the other end of said shank releasably engageable with an adjacent edge of said base flange, and means for securing the rail on said tie plate with capacity for limited vertical movement with respect to said tie plate comprising a lug secured to said tie plate and defining a pair of spaced substantially horizontally extending arms adapted to be positioned above and below the upper jaw of said anchor, whereby the upper arm provides an abutment for the top surface of the upper jaw of the anchor and exerts a shear force thereon in the event of abnormal upward movement of the rail relative to the tie plate.

4. In a railway track structure of the class described, a tie plate having an elongated slot,

a rail having a base flange adapted to rest on said tie plate, a one-piece rail anchor comprising a main body extending beneath said base flange and in said elongated slot, a return bent hook contiguous with said body and defining upper and lower jaws for releasably clamping the top and bottom surfaces of said base flange, an integral detent at the other end of said body releasably engageable with an adjacent edge of said base flange, said slot being of such dimension as to provide for the engagement of said detent with the edge of said base flange and to prevent the overdriving of said rail anchor onto said base flange, and means for securing the rail on said tie plate with capacity for limited vertical movement with respect to said tie plate comprising a lug secured to said tie plate and defining a pair of spaced substantially horizontally extending arms adapted to be positioned above and below the upper jaw of said anchor and to be subjected to shear engagement with said hook in the event of abnormal vertical motion of said rail relative to the tie plate and thereby prevent spreading of the upper and lower jaws of said anchor.

5. In a railway track structure of the class described, a tie plate having an elongated slot, a rail having a base flange adapted to rest on said tie plate, a one-piece rail anchor comprising a

5

10

15

20

25

body portion extending beneath said base flange and in said elongated slot, a return bent hook contiguous with said shank and defining upper and lower jaws releasably engageable with said base flange, and means for securing the rail on said tie plate with capacity for limited vertical movement with respect to said tie plate comprising a substantially rectangular shaped apertured lug secured to said tie plate and spanning the elongated slot therein, said lug defining a pair of spaced substantially horizontally extending arms adapted to be positioned above and below the upper jaw of said anchor said aperture and the upper arm of said lug being positioned to impart a shearing strain on the upper jaw of the anchor as distinguished from an outward flexing strain thereon.
